United States Patent Office

Des. 208,519
Patented Sept. 5, 1967

208,519

ATTACHÉ CASE

Raymond P. Stoy, White Plains, N.Y., assignor to The Leather Specialty Company, Cincinnati, Ohio, a corporation of Ohio

Filed Oct. 21, 1965, Ser. No. 87,717

Term of patent 14 years

(Cl. D87—5)

Fig. 1

Fig. 2

Fig. 4

FIGURE 1 is a side elevational view of an attaché case showing my new design, both sides of the case being identical.

The essential features of my design are shown in full lines.

I claim:

The ornamental design for an attaché case, as shown and described.
